(57) **CLAIM**

The ornamental design for a display screen or portion thereof with animated graphical user interface as shown and described.

DESCRIPTION

The patent or application file contains at least one drawing executed in color. Copies of this patent or patent application publication with color drawing(s) will be provided by the Office upon request and payment of the necessary fee.

1. Display screen or portion thereof with animated graphical user interface

1.1 : First image in a sequence of transitional images
 1.2 : Second image in a sequence of transitional images
 The broken line at the perimeter of the reproductions illustrates the display screen or portion thereof, and the remaining broken lines illustrate portions of the animated graphical user interface. None of the broken lines form part of the claimed design.

The appearance of the transitional image sequentially transitions between FIGS. 1.1 and 1.2. The process of period in which one image transitions to another form no part of the claimed design.
